E. FITZGERALD'S DESIGN FOR RAILING
and other Decorations
Pittore Ottimo del Nostro

Design 423

Frederick Fitzgerald, of, New York, N.Y.
assignor to
Silas C. Herring & John Ryer.
Letters Patent No 423. Dated, Nov. 18. 1851.

The schedule referred to in these Letters Patent making part of the same.

To all whom it may concern:

Besit known that I, Frederick Fitzgerald of the City County & State of New York, have invented a new ornamental design for railing of I do hereby declare that the following is a clear & exact description of the same, reference being had to the accompanying drawings forming part of this specification, in which;

Fig. 1, is a front view of one of the pieces forming the railing, when the same runs level, as in a balustrade or balcony.

Fig. 2, is the adjoining rail to that represented in fig. 1, from which latter it branches at a right or other angle to form the railing of a step or steps, to the said balcony composed of rails, as represented in fig. 1.

Fig. 3, is a profile of the ornaments marked G, H, taken as indicated by the line 11, fig. 1. -

Fig. 4, is a similar view of the ornaments C, D, taken through the line 22, same fig.

Fig. 5, is a transverse section of one of the branches, as seen for instance through the lines 33, fig. 1.

Fig. 6, is a vertical or longitudinal section for a portion of its length of the rail represented in fig. 2, viewed as indicated by the line 44.

Fig. 7, is a profile of the ornaments

Des. 4683

marked, m, m, fig. 2, received as seen by the line 55, and,

Fig. 8, a similar view in transverse section
of the trunk or stem, taken as denoted by the line 66.

The same letters of reference point out
similar parts.

My invention consists in a new &
original design, arrangement & configuration of the
several ornaments comprising the railing seen & referred to by letters
in the several figures; the rails, fig 1, fig 2, occupying
the relative positions towards one another, previously de-
fined to, namely, the railing for steps or stair cases, being
formed of a repetition, adjoining one another of the rail
represented in fig 2, which meet & may branch off
at right angles or otherwise with a balustrade Compo-
sed of a repetition of rails similar to fig 1.

The rail fig 1, has its central trunk or
stem A, A, with the several branches B, B, B', B', on either side
of the form or figure, represented in fig 3, consisting of
Cymas & beads, as shown & which together with the several
ornaments attached, may be repeated on the other side of
the rails, if cast double, as is the case with the rail, fig
2, which is made solid & of the same configuration on either
side, as shown by fig 6.

In fig 1, the trunk or stem has at either
outer end an ornament, C, composed of a floral or leaf device
where the stem is interrupted as it approaches the centre
are further ornaments on both halves of the stem similar
to D, from which on either side branch or fit a smaller stem
carrying a flower or scroll E; each of the branches B', B', are of
the curved shape shown in fig 1, & unite the branch B² at
right angles with the main trunk A, a fanciful device F, orna-
menting the junction of the branches, & the branches B, B.

which are also curved serving together with the straight branch B² to unite the parts thus referred to with scroll leaf & other fanciful devices, G, G, and H, of the configuration represented in the drawing & joined by heart shaped ornaments I, I.

In fig. 3, a, a, is the trunk or stem whose outline is seen more clearly in fig. 8, the outline also in cross section of the several branches, B, B, C & d, being similar, the trunk near one of its outer ends has a floral ornament e from which on either side projects the curved branch d, terminating in a circular set f, the opposite outer end of the trunk has curved arms or branches B, B, one on either side sloping as represented for accomodation of the hand bars or covering rail, these branches terminate in partly circular sets g, g, and where joining with the trunk, are met by leaf & scroll ornaments, h, h; the inner end of each half of the trunk where interrupted by the central arrangement of parts, is (each half) ornamented with a floral fanciful device K, from which jets a stem l, terminating in a scroll or floral heading as shown, & the curved branch C, one of which projects on either side from either half of the inner ends of the divided stem, is further ornamented with leaf & scroll devices m, m, that form a set at the junction of the two branches similar to C: projecting from either side of the inner ends of the divided trunk.

The several ornaments in figs. 1 & 2 not shaded or tinted, are repetitions of those more fully shown & described as will be readily seen by their corresponding outline.

(What I claim as my invention and desire to secure by Letters Patent is, &c. The design, arrangement & configuration

4

Ses. 423

of the several ornaments composing the balustrade
and step railing) branching or leading therefrom, as
represented & described.
